UNITED STATES PATENT OFFICE.

FRANK ALMSTEAD, OF CLAYVILLE, NEW YORK.

ROPE-CLAMP.

No. 881,041.

Specification of Letters Patent.

Patented March 3, 1908.

Application filed June 29, 1907. Serial No. 381,435.

To all whom it may concern:

Be it known that I, FRANK ALMSTEAD, a citizen of the United States, residing at Clayville, in the county of Oneida and State 5 of New York, have invented new and useful Improvements in Rope-Clamps, of which the following is a specification.

This invention relates to a rope clamp of that type including a cam which is adapted to 10 clamp the rope against an adjacent abutment or surface, the cam being provided with a lever or actuating arm whereby the rope can be released or gripped.

The invention has for one of its objects to 15 improve and simplify the construction and operation of devices of this character so as to be comparatively easy and inexpensive to manufacture and convenient and reliable in use.

20 A further object of the invention is the provision of a rope clamping device in which the clamping cam can be manipulated by the free end of the rope, thereby enabling the clamping device to be located out of reach 25 and still be readily controlled.

With these objects in view and others, as will appear as the description proceeds, the invention comprises the various novel features of construction and arrangement of 30 parts which will be more fully described hereinafter and set forth with particularity in the claims appended hereto.

In the accompanying drawing, which illustrates one of the embodiments of the invention, Figure 1 is a side elevation of the clamp. Fig. 2 is a longitudinal section thereof. Fig. 3 is an end view. Fig. 4 is a plan view.

Similar reference characters are employed 40 to designate corresponding parts throughout the several views.

Referring to the drawing, A designates the body of the device which is a metal structure consisting of parallel triangular plates 1 connected by a top portion 2, there 45 being an eye 3 at one end of the said portion for the purpose of attaching the body to a rope, as shown in Fig. 1 or to a hook or other fastening 4, as shown in Fig. 2. Between the plates or ears 1 is a cam 5 that is pivoted 50 on the pin 6 at a suitable point below the top portion 2 so as to permit the rope 7 to be engaged between the cams and bottom side of the top. The cam 5 is formed with a lever 8 that extends approximately at right angles 55 to the general length of the gripping face of

the cam, and is provided with an opening 9, as clearly shown in Fig. 3, for receiving the free end of the rope 7. The gripping face of the cam is formed with teeth 10 so shaped as to bite into the rope and resist a draft on 60 the latter in a direction away from the anchored end of the body A, and the under side of the top 2 has teeth 11 that coöperate with the cam to tightly clamp the rope.

In practice, the clamping device can be secured to a hook or other fastening, as shown in Fig. 2, or to one end of the rope 7, as shown in Fig. 1, where an endless clothes line or the like is desired, and it will be noted that the body A is comparatively narrow and flat on 70 its top side so as to enable the device to freely pass around guide pulleys without throwing the rope off the latter. The free end of the rope is inserted through the body of the device and over the cam and hence through the 75 opening 9 of the lever 8. To secure the free end of the rope, the lever 8 is moved by hand to the dotted line position shown in Fig. 2, to permit the rope to be drawn tight, and then by throwing the lever to the full line position, 80 the cam will tightly clamp the rope.

It will be noted that the draft on the rope in the direction indicated by the arrow will cause the teeth 10 to bite deeper and deeper into the rope and thereby resist such draft. 85 The construction of the device is such that the latter can be readily operated even when the lever 8 is beyond the reach of the operator, and for this purpose, the free end of the rope is adapted to hang at a point conveniently within the reach, so that by taking hold 90 of the rope and simultaneously pulling the latter to the left and downwardly, the parts will be thrown to the dotted line position, Fig. 2, thereby enabling the rope to be drawn 95 taut without the teeth interfering. While the rope is thus held taut, it is pulled to the right so as to cause the lever to assume the full line position and clamp the rope between the teeth 10 and 11.

From the foregoing description, taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the ap- 105 110

paratus shown is merely illustrative and that such changes may be made when desired, as are within the scope of the claims.

Having thus described the invention, what I claim is:—

A rope clamping device comprising a body or frame having parallel ears, a cam pivoted between the ears and having a gripping face coöoperating with a portion of the frame for clamping a rope or the like, teeth on the cam shaped to permit the rope to slide in one direction, a lever on the cam disposed approximately at right angles with the general

length of the gripping face of the latter and provided with an opening, means for anchoring the body to a suitable support, and a rope or the like extending over the cam and having its free end threaded through the opening of the lever.

In testimony whereof, I affix my signature in presence of two witnesses.

FRANK ALMSTEAD.
